United States Patent Office

Des. 184,813
Patented Apr. 7, 1959

184,813

PLATE OR SIMILAR ARTICLE

Takeshi Inoue, Atsuta-ku, Nagoya, Japan, assignor to Noritake Co., Inc., New York, N.Y., a corporation of
New York

Application November 29, 1954, Serial No. 33,273

Term of patent 3½ years

(Cl. D44—15)

The figure is a plan view of a plate or similar article, showing my new design.

The plate is of a conventional configuration when viewed from the side and bottom thereof.

I claim:

The ornamental design for a plate or similar article, substantially as shown and described.
